IGNITION MEANS FOR EXPLOSIVE-ENGINES.

1,251,162.

Specification of Letters Patent. Patented Dec. 25, 1917.

Application filed March 30, 1916. Serial No. 87,759.

To all whom it may concern:

Be it known that I, GEORGE R. WRIGHT, a subject of the King of England, residing at Surrey Centre, Province of British Columbia, Dominion of Canada, have invented 5 certain new and useful Improvements in Ignition Means for Explosive-Engines, of which the following is a specification.

The present invention constitutes improvements in that type of automatic ignition devices commonly called timers for internal combustion engines disclosed in the patent granted to F. W. Johnson and myself, September 8th, 1914, No. 1,109,732.

15 As is well known to those skilled in the art to which this invention refers, it is very essential in the operation of variable speed engines that the sparking of the ignition circuit should occur in the engine cylinders at the proper instant with respect to the crank position and to accomplish this as nearly as possible, manually operated control means is usually provided in order that the "spark" may be advanced or retarded as the speed of 25 the engine increases or decreases. In view of the fact that under proper manipulation of this control many advantages are derived such as the increase in the engine power, decrease of carbonization of the fuel and 30 prevention of overheating of the engine, the desirability of producing these results by elimination of the human element may be easily appreciated.

Therefore, with this end in view, I have 35 provided an ignition device which, coöperating with an engine operated shaft, embodies centrifugal governor devices arranged to automatically advance or retard the spark as the case may be in ratio with the speed 40 of the engine, said device consisting primarily of a rotor, and weight members connected to the engine operated shaft and to the rotor aforesaid whereby under centrifugal action to shift the rotor and consequently the relative position of the circuit 45 contacts of the timer device.

For a full understanding of the present invention, reference is to be had to the following description and the accompanying 50 drawing, in which:

Figure 1 is a sectional view on the line 1—1 of Fig. 2, with the cover for the relatively stationary member removed, parts being broken away and shown in section.

Fig. 2 is a vertical sectional view on the line 2—2 of Fig. 1.

Fig. 3 is a perspective view of the shell of the rotor, the cover and governor devices therefor being removed.

Fig. 4 is a sectional view of a modified 60 form of the device as constructed to constitute a contact breaker.

Fig. 5 is a detail view of one of the governor weights used in this device; and

Fig. 6 is a fragmentary sectional view 65 showing a modified form of contact segment.

Throughout the following detail description and on the several figures of the drawing, similar parts are referred to by like 70 reference characters.

Referring to the drawing, and specifically describing the invention, the numeral 1 indicates the face portion of an engine or other supporting part designed to receive 75 thereagainst the ignition device forming the subject matter of this application. The numeral 2 designates an engine operated shaft, and 3 the relatively stationary element of the timer device into which the shaft 2 extends and which member is suitably held against the surface 1 by means of a bolt 4, and a spring 5 connected at one end to said bolt and at its other end to the cover 6 for the stationary member. Said cover as will 80 be noted in Fig. 2, is provided with a central opening 7 adapted to receive the projection 8 on the end of the spring and preferably I employ a fastening member 9 extending through the spring and into the casing cover 90 6 to hold the stationary member in relatively fixed position. The said stationary member in the form of the device constituting a timer, carries a plurality of binding posts 10, one being provided generally for 95 each cylinder of the engine and these binding posts, as customary, terminate in contact segments 11 by means of which the circuit to the cylinder is automatically closed upon coöperation therewith of a contact making member. The stationary element 3 consists of a ring of insulating material in which the segments above referred to are embedded. Mounted upon the end 100 of the shaft 2 is a sleeve 12 which is fixed to said shaft by means of a key 13 or similar fastening device, so that said sleeve and instrumentalities connected therewith will re-

tate with the shaft 2 during the operation of the engine. A clamping nut 13' threaded on the end of the shaft 2 holds the sleeve against displacement from said shaft.

5 A rotor in the form of a casing 14 is loosely journaled upon the sleeve 12 and is provided with a cover plate 15 secured thereon by means of the screws or fastening members 16, these members performing a 10 dual function as will be set forth hereinafter.

15 Mounted within the casing 14, and therefore protected from dust or oil, are arranged the speed controlling means or governor instrumentalities which consists of oppositely disposed weight members 17. Said weight members are pivotally connected by pins 18 to offstanding projections 19 of the sleeve 12, and in their normal position, as when 20 the engine is inoperative, these weights extend tangentially with respect to the operating shaft 2, as clearly shown in Fig. 1 of the drawing. At the outer end each of said weights is provided with a slot 20 through 25 which the cover fastening members 16 above referred to project, these members constituting guide means for the weights in the operation of the rotor so that through the pin and slot connection thus provided said rotor 30 or casing 14 is shifted rotatably about the axis of the shaft in proportion to the speed of operation of the shaft 2 and as determined by the centrifugal action of the said weights. The casing 14 is provided with a 35 brush 21 projecting outwardly from the casing and seated within the holder 22, said brush being actuated by a spring 23 to normally hold its extremity in contacting relation with respect to the stationary element 3.

40 In the operation of this device, rotation of the shaft 2 which is actuated in a suitable manner commensurate with the speed of operation of the crank shaft of the engine, the governor devices 17 are rotated and owing 45 to the centrifugal action incident to such rotation said devices or weights tend to move from their normal tangential position toward a position radial with respect to the operating shaft, as shown most clearly in 50 dotted lines in Fig. 1. By reason of the interlocking connection between said weights and the casing, the latter is shifted as above mentioned about the axis of the shaft 2 and the extent of this relative movement depends as will be readily understood upon 55 the speed of actuation. By reason of the peculiar mounting of the weights as the speed of operation is reduced they tend to assume their normal tangential position, 60 more or less.

Incidental to the shifting movement of the rotor or casing about the axis of the shaft the brush 21 carried by said rotor is shifted so as to cause the closing of the primary 65 circuit sooner or later depending upon the

direction of shifting movement with the usual result of inducing a secondary current for producing the spark in the engine cylinders.

In order to insure the normalizing action 70 of the rotor upon reduction of speed of the engine, I provide one or more springs 24 which are connected at one end to the sleeve 12 and at the other end to the rotor casing 14. In order to overcome any difference in 75 the weight of the opposing governor devices 17 it is desirable that the tension of the springs 24 be adjustable and to accomplish this result the casing 14 is provided with notched segments 25 to which the respective 80 springs 24 are connected. It will be apparent than an end of each of said springs is adjustable circumferentially of the casing and thus the tension which will be imparted to the springs by shifting movement of the casing under action of the governor devices is subject to control.

In Fig. 6 I have illustrated a special form 90 of contact segment 11^a, said segment being made up of a plurality of materials of different resistance so that as the brush 21 passes over the segment the resistance will be increased and thereby the arc which usually occurs on the break of the circuit will be eliminated. I desire it to be understood 95 that I do not wish to be confined to this particular construction of segment for carrying out said object as the same effect may be produced in other ways than that illustrated and described in this application.

100 In Fig. 4 is shown a different type of ignition means which, however, follows the same general principle of construction as is embodied in the type shown in Fig. 1 of the drawing. That is to say, the device of Fig. 105 4 is designed as a circuit breaker and consists of the relatively stationary member 3^a which is provided with a binding post 10^a formed with a shell 22^a in which the spring actuated brush 21^a is mounted. The rotor 110 14^a in this type of device is provided with the segments 11^b formed of insulating material two of such segments being shown in the drawing. It will be readily understood 115 that as the rotor 14^a is operated the circuit 21^a over the segments 11^b.

Having thus described my invention, what I claim as new is:

1. Ignition means for internal combustion 120 engines comprising a relatively stationary member, a rotating member within the latter, an engine operated shaft on which said rotating member is journaled, centrifugally operated speed controlled means connected 125 to said shaft at one end and having connection with the rotating member at the other end whereby to shift the latter about the axis of the shaft commensurate with the speed thereof and relatively with respect to 130

the stationary member, and a circuit contact member intermediate the stationary and rotating members operable by the rotating member aforesaid.

- 5 2. Ignition means for internal combustion engines comprising a relatively stationary member, a rotating member within the latter, an engine operated shaft on which said rotating member is journaled, speed controlled means having swinging connection with said shaft and having radially shiftable connection with the rotating member permitting movement of said means about the swinging connection into position substantially radial with respect to the shaft, to thereby shift the rotating member relative to said shaft and relative also to the stationary member, and circuit control means intermediate the stationary and rotating 15 members adapted to be shifted automatically upon relative movement of the rotating member aforesaid.

3. Ignition means for internal combustion engines comprising a relatively stationary member, a rotating member, an engine operated shaft on which said rotating member is journaled, a centrifugally operated governor device movably connected to the shaft and normally arranged substantially tangential with respect thereto, means connecting said device to the rotating member whereby on movement of said governor device toward a radial position under actuation of the shaft the rotating member is 30 shifted relative to the latter, and guide means for guiding the radial movement of the governor device.

4. Ignition means for internal combustion engines comprising a relatively stationary member, a rotating member, an engine operated shaft on which said rotating member is journaled, a governor device having pivotal connection at one end with the shaft, said device being movable circumferentially 45 at its other end, and a pin and slot connection intermediate the said other end of the governor device and the rotating member for shifting the latter relative to the shaft on pivotal movement of the governor device 50 incident to actuation of said shaft.

5. Ignition means for internal combustion engines comprising a relatively stationary member, a rotating member therein, an engine operated shaft on which said rotating 55 member is journaled, speed controlled means connected to said shaft and having connection with the rotating member whereby to relatively shift the latter about the axis of the shaft commensurate with the speed thereof, and tension means connecting the rotating member with the shaft for insuring normalizing of the latter.

6. Ignition means for internal combustion engines comprising a relatively stationary member, a rotating member, an engine oper-

ated shaft on which said rotating member is journaled, speed controlled means connected to said shaft and having connection with the rotating member whereby to relatively shift the latter about the axis of the shaft 70 commensurate with the speed thereof, and tension means connected at one end to the shaft and adjustably connected to the rotating member at its other end for controlling relative movement of the rotating 75 member under control of the speed control means.

7. Ignition means for internal combustion engines comprising a relatively stationary member, a rotor disposed therein and comprising a casing, an engine operated shaft on which said casing is loosely journaled, govenor weights arranged within the casing and connected to the shaft, guide means carried by said casing and coöperating with 80 the weights aforesaid whereby to relatively shift the casing about the axis of the shaft commensurate with the speed of rotation of said shaft, and a circuit contact member carried by said casing and coöperating with 85 the stationary member aforesaid under control of the governor weights.

8. Ignition means for internal combustion engines comprising a relatively stationary member, a rotor housed within said member and comprising a casing, a removable cover for said casing, fastening means for connecting the cover thereto, an engine operated shaft on which said casing is mounted, speed control devices mounted 95 within said casing and coöperating with the fastening means for said cover, and an operative connection intermediate said control devices and the engine operated shaft, whereby to shift the casing relative to the 100 shaft upon actuation thereof.

9. Ignition means for internal combustion engines comprising a relatively stationary member, a rotating member, an engine operated shaft on which said rotating member is 110 journaled, speed controlled means connected to said shaft and having connection with the rotating member whereby to relatively shift the latter about the axis of the shaft commensurate with the speed thereof, a 115 sleeve fixed to said shaft and constituting a bearing for the casing, and means pivotally connecting said speed control devices to the sleeve.

10. Ignition means for internal combustion engines comprising a relatively stationary member having contact segments disposed thereon, a rotor coacting with said stationary member, a brush carried by said rotor for coöperation with said segments, 120 an engine operated shaft on which said rotor is mounted, means for shifting said rotor relatively about the axis of said shaft upon actuation thereof, and tension means connected to the shaft at one end and having 125 130

circumferentially adjustable connection with the rotor at the other end for controlling the shifting action of said rotor.

11. Ignition means for internal combustion engines comprising a relatively stationary member, a rotating member, and a governor device for controlling shifting move-

ment of the rotating member with respect to the stationary member and including opposing radially and circumferentially shiftable elements.

In testimony whereof I affix my signature.

GEORGE R. WRIGHT.
